[57] **CLAIM**

I claim the ornamental design for a heat dissipation fan, as shown.

DESCRIPTION

FIG. 1 is a perspective view of the heat dissipation fan showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view thereof; and,

FIG. 7 is a bottom plan view thereof.
